CLEANING AND MASSAGING DEVICE

William C. Stewart, Kenosha, Wis.

Application September 23, 1938, Serial No. 231,431

2 Claims. (Cl. 15—180)

This invention relates to a cleaning and massaging device designed primarily for cleaning the teeth and massaging the gums of a person, but it is to be understood that a device, in accordance with this invention is for use in any connection for which it may be found applicable.

The invention aims to provide, in a manner as hereinafter set forth, a device of the class referred to, including revoluble means for action on the teeth or gums for respectively cleaning and massaging them.

The invention further aims to provide, in a manner as hereinafter set forth, a device of the class referred to, including oppositely revoluble spring controlled invertible means for action on the teeth or gums for cleaning the former and massaging the latter.

The invention further aims to provide, in a manner as hereinafter set forth, a device of the class referred to, which is simple in its construction and arrangement, strong, durable, compact, having its operation conveniently controlled from the user, thoroughly efficient when used, including a revoluble element for action on the teeth and gums and with such element capable of being expeditiously inverted when desired, readily assembled, and comparatively inexpensive to manufacture.

Embodying the aforesaid aims and others which may directly or indirectly hereinafter appear, the invention consists of the novel construction, combination and arrangement of parts as will be more specifically referred to and illustrated in the accompanying drawing, wherein is shown an embodiment of the invention, but it is to be understood that changes, variations and modifications may be resorted to which fall within the scope of the invention as claimed.

In the drawing:

Figure 1 is a side elevation partly in section of the device and showing the position of the operating means, in full lines at the end of the stroke for imparting an anti-clockwise movement to the cleaning element for the teeth, the position of said means in dotted lines at the end of the stroke for imparting a clockwise movement to said element, and the position of said element, in dotted lines when inverted.

Figure 2 is a section on line 2—2 of Figure 1.

Figure 3 is a front elevation, upon an enlarged scale, of the cleaning element for the teeth.

Figure 4 is a side elevation, upon an enlarged scale, of the cleaning element and its driving spindle, and illustrating in dotted lines said element when inverted.

Figure 5 is a section on line 5—5 of Figure 1.

Figure 6 is a longitudinal sectional view, upon an enlarged scale, of the cleaning element with the bristles not shown, and

Figure 7 is a front elevation of the massaging element.

The device includes an open front casing 1 of oval contour in cross section and of the desired width, breadth and length. The casing 1 is constructed from any suitable material, preferably light metal and has a closed rounded outer end 2. The open front of casing 1 is closed by a cover 3 formed with apertured lugs 4 extending into casing 1 and secured to the latter by the countersunk screws 5. The cover 3 is provided with an outwardly directed threaded stud 6 for a purpose to be referred to.

The casing 1 has arranged therein a partition 7 extending from the cover 3 and terminating in spaced relation to the end 2. The inner end of partition 7 has a portion 8 disposed in transverse relation with respect to casing 1. The latter includes the side walls 9, 10, top wall 11 and bottom wall 12. The partition 10 and its inner portion 8, in connection with the walls and end 2 of casing 1 provides the latter with a compartment 13 at its outer end and a pair of side compartments 14, 15. The compartment 14 opens into compartment 13. The compartment 15 is substantially closed to compartment 13. The partition 7 and its end portion 8 are integral with the top, bottom and side walls of the casing 1. The end portion 8 of partition 7 is formed with an opening 16. The side wall 10 of casing 1 is provided lengthwise thereof with a slot 17.

The top and bottom walls 11, 12 of the casing 1, in proximity to casing end 2, are formed with aligned openings 18, 19. The latter is of less diameter than opening 18. The bottom wall 12 of casing 1 adjacent opposite sides of opening 19 is formed with a pair of threaded openings 20. Extending through opening 19 into chamber 13 is a bearing 21 having its lower end formed with a laterally extended apertured flange 22 which abuts the outer face of wall 12, and it is secured to the latter by screws 23 extending through the flange 22 and threadedly engaging with the walls of the openings 20.

Extending through opening 18 into chamber 13 is a vertically disposed bearing 24 for a spindle 25. The latter is formed of an enlarged circular lower portion 26 and a reduced upper portion 27 of rectangular cross section formed with a recess 28 in one side thereof. At the junction of the portions 26, 27 of the spindle a shoulder 29 of 55

segmental contour in cross section is formed. The upper end 30 of bearing 24 is of a contour the same as and overlaps shoulder 29. The lower part of the portion 26 of spindle 25 is formed with 5 oppositely extending diametrically opposed cut-outs 31 opening at the periphery and also at the inner end of the spindle.

Arranged within the compartment 13 is an oppositely revoluble driver 32 for the spindle 25. 10 The driver consists of a grooved pulley 33 seated on the upper end of bearing 21, a shaft 34 depending from pulley 33 and extending through bearing 21, a circular disc 35 integral with the upper face of, disposed coaxially with and of less 15 diameter than the pulley 33, and a keeper 36 of angular form integral with the upper face and axially of the disc 35. The lower end of bearing 24 seats on pulley 33 and encompasses the disc 35. The bearing 24 is welded to the top wall 20 11 of casing 1. Secured to the spindle 25, within in the cut-outs 31 are a pair of oppositely disposed resilient latching members 37 of like form. The said members depend from the bottom of spindle 25 and have angular lower end portions 25 37^a which coact with the keeper 36 for releasably latching the driver 32 and spindle together, whereby on the revolving of the driver, the spindle will be bodily carried therewith.

The device includes a cleaning element 38 of 30 brush-like form for the teeth. The element 38 consists of a head 39 and a flared circular row of tufts of bristle 40. The head 39 includes end portions 41, 41^a of like form consisting of circular part 41^b having oppositely disposed lateral 35 extensions 41^c, 41^d of rectangular form, and an intermediate portion 42 of greater diameter and thickness than the portions 41, 41^a. The said portions of the head 39 are arranged coaxially. The head 39 is formed with a radially disposed 40 rectangular groove 43 which opens at its end surfaces and at one side of its outer periphery. The depth of groove 43 is greater than one-half of the diameter of said head. The head 39 is formed with a bore 44 disposed at right angles 45 to and intersected, at its transverse median by the groove 43.

The extensions 41^d of the head end portions are provided with diametrically disposed aligned spaced threaded sockets 45, communicating at 50 their inner end with openings 46 which communicate with the groove 43. The bristles 40 are anchored at their inner ends into that part of the outer end surface of the head portion 42 which borders the head side portions. 55 The outer or reduced portion of the spindle 25 is mounted in the groove 43 of the head 39. The recess 28 in spindle 25 is to selectively align with the openings 46 of the head 39. The latter and spindle 25 are latched together, and for each 60 purpose headed latching members 47 are arranged in sockets 45, extend through openings 46 and selectively engage in the recess 28. Arranged within the sockets 45 are holding springs 48 for releasably retaining a member 47 in the recess 28. Threadedly engaging with the walls of the sockets 45 are threaded compressing and holding members 49 for the springs 48.

The cleaning element 38 is invertible with respect to spindle 25, and for such purpose, a trunnion pin 50 is mounted in bore 44, extends through the groove 43 and an opening 50^a formed in the portion 27 of spindle 25. The spring controlled latching members coact with the recess 28 for latching element 38 in its selected position. The 70 groove 43 provides a clearance when inverting

element 38 and when restoring it to normal position.

The device includes a reciprocating spring controlled operating means 51 for the driver 32, and such means consists of a tubular slide 52 which 5 is mounted on and conforms in contour to the outer periphery of casing 1, an oppositely shiftable cable 53 for revolving the driver 32 in a clockwise and an anti-clockwise direction, a controlling spring 54, a flanged thimble 55 and a 10 combined cable coupling and takeup means 56.

The means 56 is anchored to the inner face of the slide 52 and extends through the slot 17 into the compartment 14. The means 56 consists of a yoke-shape member 57 anchored by the screws 15 58 to the slide 52. The arms of member 57 ride against the partition 7 and are formed with aligned openings through which extends a threaded bolt 58^a carrying a take-up nut 59 on its outer end. The inner end of bolt 58 is connected within the compartment 14, as at 60, to the outer end of the cable 53. The latter is arranged in the compartments 13, 14 and 15 and passes around the pulley 33 in the groove of the latter. The cable 53 also passes through the 20 opening 16, in the portion 8 of partition 7. The thimble 55 is mounted on and secured to the inner end terminal portion of the cable 53, and its flange, indicated at 61, rides against the walls of the compartment 15. The spring 54 is of the 25 coiled type, and it is mounted on the cable 53 between the flange 61 of the thimble 55 and the portion 8 of the partitions 7. The said portion 8 constitutes an abutment for the spring 54, for the purpose of compressing the latter when cable 35 53 is pulled in a direction to impart a clockwise movement to the driver 32.

Welded to opposite sides of the slide 52 are a pair of aligned oppositely extending finger receiving rings 62 which form elements of the operating means 51.

Detachably connected to the stud 6 is a threaded sleeve 63 which is formed integral with a thumb receiving ring 64.

With reference to Figure 7, a gum massaging 45 element of brush-like form indicated at 65, is shown and it is of the same construction as element 38, with this exception that the bristles 66 of element 65 are rubberized.

The device, in accordance with this invention, 50 has been devised as a result of careful study of the necessity for prophylaxis, care and preservation of teeth. Dentists throughout the world use a revolving type of instrument for cleaning teeth but vastly different from this device. The operation of the device is simple, rapid and thorough. It minimizes the separation and destruction of the protective tissue collar membrane around the teeth which is attached to the gums holding them in close apposition to the teeth. Tooth brushes 60 now in use break down this membrane and separate the gums from the teeth by pushing the gums upward and downward thus opening up new avenues for infection which result in decay and destruction of teeth.

The revolving type of brush forming an element of this invention follows along the margin of convexity of the gums around the upper teeth and along the margin of concavity of the gums around the lower teeth as they dip pointedly into 70 the inter-dental spaces, thus cleansing the entire circumference of the exposed surface of the teeth. The device is so devised that the user can cleanse either the anterior or posterior surface of the teeth with either hand from any convenient pos- 75

tural position without impinging upon the lips, face or chin of the user.

Relative to the operation of the device, the thumb is inserted into the ring 64 of the device 5 with the element 38 pointing toward the teeth, at the same time the user inserts the index finger into the ring 62 which is toward the user, the second finger is inserted into the opposite ring 62. The device is now in position for operation. As 10 the user separates his lips holding the upper and lower teeth in close apposition the brush is pressed against the teeth lightly, he now pulls toward the thumb, the two rings into which are inserted the index and second fingers, as he pulls these rings 15 62 he will note that the brush revolves in one direction, he now releases the pulling operation slightly permitting the two rings 62 to move upward which is caused by the recoil of the spring. As the rings 62 move upward, the user notes that 20 the brush revolves in the opposite direction. The brush can be moved either slowly or rapidly over the surface of both the upper and lower teeth at the same time, and can be kept in a constant revolvable motion. The ease, extent, rapidity, force 25 and efficiency of this operation depends entirely upon the user.

The cleansing of the posterior surface of the teeth is accomplished in the same way except that the operator inverts the element 38. This 30 must be done to cleanse the posterior surface of the teeth. The direction of the element 38 is reversed until it locks in the spindle. The user now notes that the bristles point away from instead of toward the teeth. When this is accomplished he now opens his mouth slightly so that 35 the upper and lower teeth are separated sufficiently to permit the brush to pass between and beyond the upper and lower teeth, he now closes the mouth so that the upper and lower teeth come 40 in contact with the instrument, the lips being closed lightly at the same time, keeping in mind constantly that ease of operation will depend entirely upon the freedom of the brush in the mouth. The user now notes that the brush in its 45 entirety is back of the teeth with the bristles pointing toward the posterior surface of the teeth. He is now ready for the same operation as was

accomplished in cleansing the anterior surface of the teeth.

When massaging the gums the element 65 is employed with the same type of operation as that used in cleansing the teeth. 5

The elements 38, 65 may be cleansed without removing or the user may remove them easily by pulling the brush upward which is attached to the spindle, disconnect the latter and then clean the brush. The latter spindle jointly forms one 10 unit.

What I claim is:

1. In a cleaning and massaging device, a brush element including a head having a radial groove extending the entire width of the head, a revolvable spindle extending into and co-acting with walls of said groove for revolving said element, means mounted in said element at right angles to and extending through said spindle for pivotally supporting and permitting of the inverting of 20 said element relative to said spindle, said brush element including a flared circular row of tufts of bristles secured to and projecting from one end of said head, and said element and spindle having co-acting means for selectively latching the element to the spindle in normal and inverted positions. 25

2. In a cleaning and massaging device, a brush element comprising a head having a pair of end portions and an intermediate portion projecting 30 laterally beyond said end portions, said head having a groove opening at the end surfaces and at one side of the periphery thereof, said end portions being formed with sockets opening into said groove, a spindle extending into said groove for 35 revolving said head, a trunnion mounted in said head and extending through said spindle for pivotally supporting the head, latching members mounted in said sockets for extension into said groove, said spindle being provided with means 40 co-acting with said latching members for selectively latching the head in normal and inverted positions to said spindle, and a flared circular row of tufts of bristles secured to said intermediate portion and encompassing in spaced relation and 45 projecting beyond one of said end portions.

WILLIAM C. STEWART.
